UNITED STATES PATENT OFFICE.

WILLIAM DAVID McCORMACK, OF NASHVILLE, TENNESSEE.

WATER-GAGE.

1,175,784.

Specification of Letters Patent. Patented Mar. 14, 1916.

Application filed April 22, 1915. Serial No. 23,195.

To all whom it may concern:

Be it known that I, WILLIAM DAVID McCORMACK, a citizen of the United States, residing at Nashville, in the county of Davidson and State of Tennessee, have invented 5 certain new and useful Improvements in Water-Gages; and I do hereby declare the following to be a full, clear, and exact description of the invention, such as will enable others skilled in the art to which it appertains to make and use the same.

The present invention relates to water gages, and has for an object to provide an improved water gage which will be constructed 15 to provide a plurality of sight openings whereby the water level may be observed by the engineer and fireman in their respective positions in the locomotive cab, and may be observed through a central opening from the deck of the locomotive.

Another object of the present invention resides in providing an improved water gage constructed of few and simple parts readily united and disassembled to renew 25 glasses, and to provide an improved water and steam tight joint adapted to be adjusted as required.

With these and other objects in view the invention consists in the novel details of 30 construction and combinations of parts more fully hereinafter disclosed and particularly pointed out in the claim.

In the accompanying drawings forming a part of this application, and in which 35 similar reference symbols indicate corresponding parts in the several views: Figure 1 is a side elevational view of a water gage constructed in accordance with the present invention. Fig. 2 is a longitudinal sectional view taken on the line 2—2 in Fig. 3. Fig. 40 3 is an end elevation of the improved water gage; and Fig. 4 is a transverse sectional view taken on the line 4—4 of Fig. 1.

Referring more particularly to the drawings, the casing of the improved water gage is divided longitudinally, and constructed of a pair of sections 1 and 2 assembled together as hereinafter described, and connected in the boiler circuit by nipples 11 formed with 50 hexagonal or other enlargements 10 for engagement by a suitable tool to connect and disconnect the same.

As advantageously disclosed in Fig. 4, the front section 1 of the casing is con-

structed three-sided and provided with 55 sight openings 7, one in each side thereof, whereby the engineer and fireman from their respective positions in the locomotive cab may observe the height of the water therethrough, and whereby the water level 60 may be also observed from the deck of the locomotive from the central sight opening. The section 1 is further provided with shoulders 16 and flanges 17 extending thereabove for receiving the base section 2 of the 65 casing, as will be apparent from an inspection of Fig. 4.

In the section 1 of the casing is located the water glass 8, constructed complementary 70 of the casing section and supported therein by gaskets 14 interposed between the same and the interior wall of the casing section. The water glass 8 is preferably formed substantially semi-circular on its interior, and may be corrugated as shown in Fig. 4, if 75 desired. Between the base section 2 of the casing and the water glass 8 are provided complementary grooves for receiving a packing 13, which may be round as shown, or of other desired cross sectional configuration, 80 and the same is arranged to provide a water and steam tight joint between the respective parts.

The casing sections 1 and 2 are adjustably secured together by yokes 3 straddling the 85 base section 2 and formed at their opposite ends into eyes 9, the latter being arranged to be received between corresponding pairs of perforated ears 6 projecting laterally from the front section 1 of the casing. The 90 yokes 3 may be of any suitable number, preferably three, as herein shown, and are secured in position by rods 5 passed through the alining eyes in the several eyes 9 and ears 6, as will be understood. The 95 bolts 5 are preferably headed, as indicated at 12, and may be provided with any suitable devices for maintaining the same in position and preventing their accidental displacement during use.

The yokes 3 are provided with set screws 4, engaging the base section 2 of the casing, and may be tightened as required to force the sections together and compress the packing 13 to provide a tighter joint in the 105 event of leakage. At each end thereof the front section 1 of the casing is advantageously formed with bosses or enlargements

15, for providing extensive surfaces for the accommodation of wedges or other suitable instruments for prying apart the casing sections when it is desired to disassemble 5 the water gage.

The improved water gage may be quickly disassembled by loosening the set screws 4 and withdrawing the rods 5 from their engagement with the respective eyes 9 and 10 ears 6, whereupon the yokes 3 may be removed and the casing sections 1 and 2 pried apart. The water glass 8 may then be removed, cleaned, and replaced, or substituted by a fresh glass and the packing 13 15 and 14 may be renewed, as required, and the base section 2 again inserted between the flanges 17 of the front section 1. The yokes are now replaced and the rods 5 again inserted, when the set screws 4 may 20 be tightened to secure the required amount of pressure on the gasket 13 and the water gage connected in the boiler circuit, as will be now understood.

It is obvious that those skilled in the art 25 may vary the details of construction and arrangements of parts without departing from the spirit of my invention, and therefore I do not wish to be limited to such fea-

tures except as may be required by the claim.

I claim:

A water gage comprising a casing constructed of a base section and a front section provided with a plurality of sight openings, a channeled glass located in said front section and arranged to be observed through said sight openings, a packing interposed between said base section and glass, pairs of perforated ears projecting from said front section, yokes straddling 40 said rear section and provided with eyes arranged to be received between said pairs of perforated ears, rods passing through the alining openings in said perforated ears and eyes for securing the casing sections together, and means for forcing said casing sections together to compress said packing and form a tight joint, substantially as described.

In testimony whereof, I affix my signature, in presence of two witnesses.

WILLIAM DAVID McCORMACK.
